Inventor: Parker R. Wylie

UNITED STATES PATENT OFFICE.

PARKER R. WYLIE, OF CHELSEA, MASSACHUSETTS.

UMBRELLA.

SPECIFICATION forming part of Letters Patent No. 496,504, dated May 2, 1893.

Application filed May 15, 1891. Serial No. 392,874. (No model.)

To all whom it may concern:

Be it known that I, PARKER R. WYLIE, a citizen of the United States, and a resident of Chelsea, in the county of Suffolk and State of Massachusetts, have invented a certain new and useful Improvement in Umbrellas, of which the following, taken in connection with the accompanying drawings, is a specification.

The object of my invention is to facilitate the removal of divers parts in the repair thereof, to strengthen the construction and insure increased durability with a decreased expenditure. I attain these results in the manner hereinafter described and illustrated in the drawings, wherein—

Figure 1, exhibits the "runner-tube" and connections in longitudinal section, upholding and adjusting the "spreaders" radially surrounding the staff in the ordinary way. Fig. 2, is a similar view, illustrating the notched-tube supporting the attached ribs adjacent to the end of said staff or stick. Fig. 3, designates a transverse section on line $x-x$ of the parts assembled in Fig. 2. Fig. 4, is an assemblage in perspective of the retaining ring, the semi-circular notch-piece and the polygonal, or many sided, ring confining the ribs. Fig. 5, embraces two modified constructions of the aforesaid notch-pieces. Fig. 6, is an elevation of the handle with my sliding collar, automatically confining the terminals of the ribs. Fig. 7, constitutes perspective views of the various pieces forming said collar before organized for their purpose.

Referring to the letters and numerals of reference, A designates the stick or staff surrounded, as in Fig. 1, by the runner tube indicated as B, the top end of which is turned outwardly so as to produce an annular flange C, which is provided with radial slots D, for the reception of, and corresponding to, the number of spreaders desired, two only of the latter E, E, appearing in proper adjustment beneath said flange C, where they are collectively held by the polygonal ring F, which in turn is supported by two or more quadrantial or semi-circular notch-pieces G, (one of which may be observed in Fig. 4,) slotted in a manner identical with said runner tube as at D², the flange of which, C², is however turned inwardly, and of sufficiently reduced semi-circumference to rest within the flange C of said

runner, when these parts are in juxtaposition. The conformation of runner tube B, is clearly seen in Fig. 1, the lower end being reflexed inwardly, as at H, to provide a circumferential bearing along the staff A, a depression I, in part circular or otherwise, being formed around the runner tube adjacent to and beneath the flange C, the inner surface of which, H², serves identically and for the same purpose as the part H, while the depression proper receives the corresponding part J of the notch-piece G, said depression outwardly serving also as a pocket, holding the retaining spring ring K firmly in its place, after its adjustment over said notch-piece in the final operation of confining the polygonal ring F and the stretchers E, thereon strung, the latter swinging within the slots D, D², formed in the flanges of both notch-pieces and runner tubes, which slots in their final adjustment are interposed one above the other.

The bead L in the runner tube, while imparting additional strength, serves also as a rest for the lower rim of said notch-pieces, and facilitates their adjustment. The slot in said runner tube for the admission of the ordinary resilient wire upholding the runner when the umbrella is expanded will be observed at M.

In the description of my top-piece N, supporting the ribs O, illustrated in Figs. 2 and 3, the construction of the flanges and slots is identical with that of the runner tube B, as also the notch pieces P. In the latter, however, I make the shank dissimilar to the piece G, being merely semi-cylindrical, and held in position while supporting the polygonal ring F, with the ribs O, by the sliding tube Q surrounding the top-piece N. The latter may or may not have a bead at its lower end to prevent the withdrawal of said tube Q, after it is placed over the top-piece N.

To receive the notch-pieces P, I expand sufficiently the upper half Q² of said tube, to form an annular chamber within.

Fig. 2, depicts the parts assembled. The sliding tube retaining said notch-pieces is confined to the top-piece and staff in any preferable way, as R. To liberate the ribs or stretchers, in repairing, the part Q is moved to the position shown at Q³, and in Fig. 1, the ring K would assume a position as at K³. Obviously,

the interchange of said parts K and Q, or the substitution of one for the other would not affect the spirit of my invention. In the construction of the polygonal ring F, I prevent in 5 an appreciable measure the wear of the contacting surfaces, by presenting the stretchers and ribs at a right angle with said ring, also obtaining a firmer support to the former.

I now proceed to the description of my device retaining the terminals O² of the ribs against the staff A. The cylinder S receives consecutively the push ring T and the stationary ring U, over which is placed the crimped or indented ribbon or wire V of spring metal, 15 formed substantially as illustrated. The projecting spring loops V² enter the slots U² exteriorly from below, and are held therein by the collar W, which may be pinned or otherwise secured to the cylinder S. The parts 20 being thus assembled are then placed over the staff, previous to attaching the handle. Here the loops V² receive the terminals O² in the manner illustrated in Fig. 6, when it is desirable to temporarily confine the ribs. The 25 manual operation downward of the push ring T, through its conical surface T², simultaneously releases said terminals when spreading the umbrella. The friction necessary to a proper retention of said ring T, I secure 30 through its thin spring T³, or, I may with equal facility attach permanently to the runner B, limited by a stop-pin 13, said loops V² with said push ring T, embracing the runner upon which it would slide, as observed in dotted 35 lines, Fig. 1, and in the manner previously described. This arrangement would dispense with said parts S and U, and indeed may be a preferable construction. I will add that, 40 exclusive of the rings F and K, I should preferably select sheet or pressed metal, to embody the several features constituting my invention.

The modifications shown in Fig. 5 are equivalents for the notch-pieces, embodying 45 inexpensively a method of securing the ring F, the notch-piece 8 being provided alternately with flanges 9 and spaces 10, while the runner tube 11 is similarly constructed, the piece 8 permanently attached near the top of 50 the staff, the runner tube flange (when in place) occupying the space 10 as illustrated; or said flanges, if a cheaper and permanent form is desired, may be flanged inward and outward as at 12, necessitating the bending 55 of every other flange. I do not, however, consider these forms of construction valuable.

I am cognizant that runners and notch-pieces have been constructed with abutting flanges, as evidenced in Letters Patent No. 60 199,638, of date January 29, 1878, but I am not aware that flanges have been used for this purpose, and in the manner hereinbefore de-

scribed, *i. e.*, to lie one within the other when assembled. I am also aware of the construction exhibited in Letters Patent No. 185,198, 65 of December 22, 1876, as also Letters Patent No. 359,844, granted March 22, 1887. Any features therein shown I disclaim as forming part of my present invention.

What I claim is—

1. In a tip retainer for umbrellas, the herein-described push ring provided with a conical exterior lower half, the stationary ring provided circumferentially with vertical slots, the crimped ribbon spring seated in said slots, 75 a collar retaining said ribbon in place, and the cylinder adapted to support said rings upon which the parts are mounted to confine, or to liberate simultaneously the terminals of the umbrella ribs, substantially as herein described.

2. As a complete article of manufacture a runner, the lower portion of which adjacent to staff is provided with an inturned basal bearing, an exterior beaded rest, and a circumferential depression in combination with and to receive two removable notch pieces, 85 flanged and circumferentially slotted to retain a series of spreaders in the manner herein claimed and specified.

3. In an umbrella runner provided with in-turned bearings, beaded rest, and circumferential depression, the flanged and slotted top thereof, in combination with two or more notch-pieces provided with an in-turned 95 flanged top similarly slotted, and a depression to receive a retaining ring, co-acting therewith as herein set forth.

4. In combination with two semi-circular flanged and slotted notch-pieces having a circumferential depression on their shanks, 100 adapted to receive a retaining spring ring, the beaded and flanged runner tube slotted in a manner substantially as hereinbefore described to retain the spreaders in the relative 105 position as set forth, and a flanged and slotted top, the retaining spring ring and the beaded, flanged and slotted runner substantially as illustrated and described.

5. In an improved umbrella, the runner B 110 as hereinbefore described, provided with a movable ring T and an immovable spring looped ring V, arranged and combined to simultaneously confine or liberate the terminals O² of the ribs O, substantially as specified. 115

In testimony whereof I have signed my name to this specification, in the presence of two subscribing witnesses, on this 14th day of May, A. D. 1891.

PARKER R. WYLIE.
